UNITED STATES PATENT OFFICE.

PHILO N. FRENCH, OF PITTSBURG, PENNSYLVANIA.

MANDREL FOR SPRINGS.

SPECIFICATION forming part of Letters Patent No. 349,427, dated September 21, 1886.

Application filed June 19, 1886. Serial No. 205,732. (No model.)

To all whom it may concern:

Be it known that I, PHILO N. FRENCH, a citizen of the United States, residing at Pittsburgh, in the county of Allegheny and State of Pennsylvania, have invented or discovered certain new and useful Improvements in Mandrels for Springs, of which improvements the following is a specification.

In the accompanying drawings, which form a part of this specification, Figure 1 is a view in side elevation of an ordinary spring-coil machine having my improved mandrel mounted therein. Fig. 2 is a view in elevation of the mandrel and its supporting-arbor. Fig. 3 is a view in elevation of the mandrel on an enlarged scale.

In forming "keg-shaped" springs—*i.e.*, tapering from the center to the ends—the practice is to coil the spring on an iron or steel mandrel, cylindrical from one end to the center and tapering from the center to the opposite end. The spring thus formed is then removed from the mandrel, and the coils at the end formed on the cylindrical part of the mandrel, after being properly heated, are "beaten down," as it is termed, by hand, to produce the desired taper at that end of the spring.

The invention herein relates to certain improvements in mandrels for forming keg and other irregularly shaped springs, whereby such springs may be wound entirely on the mandrel, thereby dispensing with the hand-work now necessary; and to this end the invention consists in the construction substantially as hereinafter described and claimed.

The difficulty heretofore experienced in the manufacture of springs larger at the center than at the ends consisted in the impossibility of removing the mandrel from a completed spring; hence the necessity of partially forming the spring by hand. To avoid the expense incident to the old method, I now propose to form the mandrel 1 of wood or other easily-destructible material.

In coiling springs with my improved device the mandrel is first formed in any desired shape by turning from a block of wood, preferably of a hard close-fibered nature. This mandrel, through which a hole is bored, is then slipped onto the arbor 2, and the end of the arbor then placed in the revolving

heads 3 and 4, the latter being mounted in a journal-block, 5, constructed to slide upon bars 6, arranged longitudinally of the bed of the machine. The block 5 is moved back and forth on the bars 6, to insert and remove the arbor, by the lever 7 and toggle-bars 8, the revolving heads 3 and 4 being provided with sockets for the reception of the squared ends of the arbor 2.

On the bed of the machine is mounted a carriage, 9, for the holding and guiding of the bar or rod during the coiling operation, said carriage being moved along the bed by the screw 10, which is rotated by suitable gearing from the rotating head 3.

In coiling springs the end of a heated rod or bar is passed through a suitable guide in the carriage 9 and inserted between the arbor and the dog 11, secured to the head 4. Power is then applied to the head 3, to rotate the same, and with it the arbor and head 4, thereby wrapping the rod around the mandrel, which fits sufficiently tight on the arbor to rotate therewith. As the coiling proceeds the carriage 9 is moved along the bed, thus distributing the coils along the mandrel, the rapidity of movement of the carriage determining the pitch of the coils. After the rod has been coiled on the mandrel the arbor is removed from the heads and the mandrel forced off the arbor. The mandrel, with the rod or bar coiled thereon, is then placed in a furnace and the mandrel burned out, leaving a perfectly-coiled spring, ready for the finishing operation.

In lieu of wood, any other suitable material capable of being destroyed by some agency not injurious to the coils may be used in forming the mandrel.

No claim is made to the machine herein shown and described, as it is a machine now in general use.

I claim herein as my invention—

A wooden mandrel for coiling springs, having an enlarged central portion and tapering ends, substantially as set forth.

In testimony whereof I have hereunto set my hand.

PHILO N. FRENCH.
